W. H. McCARRY

OIL BURNER

Filed Dec. 12, 1923

UNITED STATES PATENT OFFICE.

WILLIAM H. McCARRY, OF PITTSFIELD, MASSACHUSETTS.

OIL BURNER.

Application filed December 12, 1923. Serial No. 680,202.

To all whom it may concern:

Be it known that I, WILLIAM H. McCARRY, a citizen of the United States, residing at Pittsfield, in the county of Berkshire and State of Massachusetts, have invented certain new and useful Improvements in Oil Burners, of which the following is a specification, reference being had therein to the accompanying drawings.

10 This invention relates to an oil burner, and the object of the invention is the production of a simple and efficient oil burning device which comprises a minimum number of parts and which is practical in operation.

15 With this and other objects in view, my invention comprises certain novel combinations, constructions and arrangements of parts as will be hereinafter described, illustrated in the accompanying drawings, and 20 more particularly pointed out in the appended claim.

In the drawings:

Figure 1 is a vertical, longitudinal, sectional view of a device constructed in accordance with the present invention, while

Figure 2 is a top plan view of the same, showing the crown plate removed.

Figure 3 is a view, in side elevation, while,

Figure 4 is an end view, in elevation, 30 of the device.

Figure 5 is a fragmentary, sectional view of a modified form of the burner, showing particularly the pipe that acts as a vaporizer.

35 Figure 6 is a view, in side elevation, of one of the sections of a stand or base, showing an oil burner in position thereon.

Figure 7 is a top plan view of a sectional stand.

40 Figure 8 is a sectional view, taken on line 8—8, Fig. 7, and looking in the direction of the arrows.

Figure 9 is a fragmentary plan view of the crown plate that fits into the bottom of 45 the device.

Referring to the drawings by numerals, 1 designates the body of the device, which is provided around its sides with preferably four outwardly-extending bosses 2, and extending through each boss is a vertical feed or supply pipe 3; each supply pipe 3 has its ends extending below the bottom of the boss in which it is positioned, as shown in Figs. 3 and 4, so that the pipe may be 50 suitably connected to a source of supply. The upper ends 4 of the supply pipes 3 are

bent downwardly in the form of a "goose neck" so that the supply of oil is discharged downwardly into the uppermost groove 5 of the body 1, the body being provided with a plurality of "stepped" or "tiered" grooves 5 for receiving the oil as it flows from the upper groove to the next groove.

Formed upon the top edge of the body 65 1, above the bosses 2, are upstanding curved flanges 6 which act as shields around the "goose neck" ends 4 of the supply pipes.

Resting upon the top of the body is a suitable cover 7 which has legs 8 (dotted 70 lines) so that the cover 7 will not fit tight upon the top of the body, whereby vapors or flames can pass from under the cover 7.

An integral base flange 9 is formed upon the body and this base flange is provided 75 with a plurality of horizontal apertures 10 that allow air to enter the burner. An upstanding flange 11 is formed upon the bottom of the body 1 about the large air inlet opening 15 and pin studs 12 are placed 80 upon the bottom of the body (Fig. 1) for receiving the bifurcated ends 13 (Figs. 1 and 9) of the crown plate 14.

In Fig. 5 there has been shown a modified construction. In this form of burner 85 the bosses 2 are omitted and the bottom of the burner is provided with a boss 16 having an opening formed therethrough to receive a distributing pipe 17 and supply pipe 18. This pipe 17 takes the place of 90 the pipe 3 and is extended upwardly and provided with a curved upper end portion terminating above the upper groove 5 in the walls of the body. The oil will therefore be heated when passing through the 95 pipe 17 and will be quickly vaporized in the grooves 5.

The sectional "base" or stand shown in Figs. 6 to 8 comprises sections 19 and 20; section 19 being provided with a plurality 100 of apertures 21 into which lugs 22 of section 20 extend to lock the sections together, as shown in Figs. 7 and 8. The sections 19 and 20 are provided with depending flanges 23, which flanges act as legs. Upstanding flanges 24 are formed upon sections 19 and 20 to prevent displacement of an oil burner 25, after it is seated within the flanges, on the sectional stand, as shown in Fig. 6. This sectional structure of a 110 stand permits ready insertion of the same in a furnace or stove, as one section at a

time can be placed through the door, and then after insertion the parts can be quickly assembled.

It is to be understood that I can make the body of my burner square, rectangular or in any preferred shape.

Where the base supporting flange 9 is not sufficient, then I can use my sectional stand as shown in Fig. 6.

10 The operation of the device will result in a saving of fuel (oil) because of the complete combustion and the construction is comparatively simple.

15 It is to be understood that the flanges or shields 6 prevent oil running onto the outside of the body.

20 Further, the top or cover 7 will assist in mixing air with the vapors and results in the flames being forced out over the sides 25 of the body into the fire-box of the stove or furnace in which the burner is operated.

There is an advantage in forming the enlarged portion or boss 16 (Fig. 5) on the bottom, for the bottom can be made of 25 comparatively thin material, whereas a thicker portion is needed for receiving the abutting ends of pipes 17 and 18.

30 It is also to be understood that by reason of the feed or supply pipes 3 passing through the bosses 2, the oil is greatly vaporized since when the burner is operated these bosses will be greatly heated, resulting in the oil passing through pipes that 35 act as vaporizers, on the same principle as pipes 17; consequently, the oil, when the

burner is operating, will be discharged into the body in practically a vaporized condition, ready for burning without any loss of fuel.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claim.

What I claim is:

In a device of the class described, the combination of a body provided with a bottom and upstanding walls, one of the walls having its inner surface provided with horizontally extending grooves positioned one above another, said bottom provided with a guarded air inlet opening and between the opening and grooved wall provided with a thickened boss having an opening therein, a distributor pipe in said body and having its lower end extending into the opening in said boss and its upper end portion curved and terminating above the upper groove for depositing oil therein, and a supply pipe having its inner end extending into said boss for supplying oil to said distributor pipe.

In testimony whereof I hereunto affix my signature.

WILLIAM H. McCARRY.
